The ornamental design for a flashlight, as shown and described.

DESCRIPTION

FIG. 1 is a left side elevational view of a flashlight showing a first embodiment of my new design; and, FIG. 2 is a left side elevational view of a flashlight showing a second embodiment of my new design.

In each of the embodiments, the design is rotationally symmetrical but for existence of the bottom and opening features which show in FIGS. 1-2.

The lens assembly which would be visible in front elevation is conventional in appearance and forms no part of the design.
